UNITED STATES PATENT OFFICE.

JAMES W. MELOON, OF BROCKTON, MASSACHUSETTS, ASSIGNOR TO THE UNITED SHOE MACHINERY COMPANY, OF PATERSON, NEW JERSEY.

SHOE-SEWING MACHINE.

SPECIFICATION forming part of Letters Patent No. 644,620, dated March 6, 1900.

Application filed May 21, 1898. Serial No. 681,320. (No model.)

To all whom it may concern:

Be it known that I, JAMES W. MELOON, a citizen of the United States, residing at Brockton, in the county of Plymouth and State of 5 Massachusetts, have invented certain new and useful Improvements in Shoe-Sewing Machines; and I do hereby declare the following to be a full, clear, and exact description of the invention, such as will enable others skilled 10 in the art to which it appertains to make and use the same.

The present invention relates to shoe-sewing machines, and more particularly to chain-stitch hook-needle machines used to unite 15 the upper and the outsole of a turn shoe or the welt and the lasted upper and insole of a welted shoe.

In an application filed by me of even date herewith, Serial No. 681,319, I have described 20 a chain-stitch hook-needle sewing-machine in which the slack thread of the loops of thread forming the stitches is removed by drawing upon the loop of thread held by the needle in a direction which will pull said thread away 25 from the closed end of the loop of the preceding stitch or in the direction of the feed of the work. In said machine is shown a separate instrumentality, which is designated therein as a "loop-shortener," to engage the loop of 30 thread drawn out by the needle and exert the loop-shortening pull thereon. In the present machine instead of having a separate instrumentality to engage the loop of thread drawn out by the needle to exert the loop- 35 shortening pull thereon I have arranged the needle-segment upon a movable slide which moves laterally across the front of the machine, so that after the needle has drawn up its loop of thread it will be moved laterally 40 in the direction of the feed, so as to exert a pull on said loop in such a direction that the closed end of the loop of the preceding stitch will not be engaged and frictionally clamped against the work by the loop of thread held 45 by the needle, whereby the slack in the loop of the preceding stitch will be removed, all as will be hereinafter specifically set forth.

The present invention consists of the devices and combination of devices which will 50 be hereinafter described and claimed.

The present invention is illustrated in the accompanying drawings, in which—

Figure 1 shows a front elevation of the upper part of a hook-needle chain-stitch machine embodying the same. Fig. 2 is a side elevation of the machine as illustrated in Fig. 1, and Fig. 3 is a diagrammatic view illustrating the operation of the needle in setting a stitch.

Similar letters and numerals of reference 60 indicate corresponding parts throughout the several views.

In the drawings, A represents the base-plate of the head of the machine, which, as usual in machines of this character, is mounted 65 upon a stand or column A', a portion only of which is shown.

Projecting upward from the base A are the standards a, which carry suitable bearings a', in which is mounted the main shaft a², carrying suitable cams 1, 2, and 3 to actuate the moving parts of the machine and which may be rotated by any suitable or convenient means. Along the front of the base-plate A is a vertical stand or frame a³, and supported 70 by the standards a and frame a³ are suitable arches a⁴, which carry suitable bearings a⁵, in which is mounted the shaft a⁶, upon which are fulcrumed various moving elements of the machine, as will be further described. 75

Inasmuch as the present invention resides more specifically in the needle mechanism I will before describing such mechanism describe such parts of the machine herein illustrated which in and of themselves form no 85 part of the present invention, but which represent a typical chain-stitch hook-needle sewing-machine, and which parts have been merely illustrated in order to convey a clear idea of the construction, organization, and 90 mode of operation of such a machine embodying the present invention.

The looper is shown at C and is mounted to rotate in a bearing c, projecting downward and backward from a guide c' in the bracket 95 B, the said bracket being projected from the front of the frame a³. The looper is rotated by means of a rack c², which is reciprocated along the guide c' by means of a link c³, connected to a lever c⁴, which is fulcrumed at c⁵ 100

- upon the base-plate A of the machine and which has a cam-roll c^6 engaging a cam-path (not shown) in the left-hand face of the cam 2 on the shaft a^2 . The upper end of the looper 5 C is provided with a pinion (not shown) which meshes with the rack c^2 , whereby as said rack is reciprocated the looper will be caused to oscillate and throw the thread around the needle.
- 10 D represents a suitable channel-guide which is fixedly secured to the bracket B, and E represents a back gage which is yieldingly pressed forward and locked at times by any usual or preferred form of mechanism common to such devices in the prior art.
- 15 F represents a feed-point which is secured in any suitable manner to an arm f, carried by one end of a rock-shaft f', mounted in a bearing f², carried by a feed-slide f³, which 20 slide is reciprocated in a guideway f⁴ in the front of the frame a³. Upon the left-hand end of the rock-shaft f' is a segmental gear f⁵, which engages a segmental gear f⁶ on the short arm of the lever f⁷, which carries a cam-roll f⁹, engaging a cam-path (not shown) in the side of the cam 3 on the shaft a², the arrangement being such that a rocking of the lever f⁷ will by means of the segmental gears f⁵ and f⁶ rock the shaft f' and impart an up-25 and-down movement to the feed-point F to engage and disengage the work. The lateral movement is imparted to the feed-slide f³ by means of a double-arm lever f¹⁰, which is fulcrumed at f¹¹, the front arm of which is slotted (see Fig. 1) and engages a stud f¹² on the feed-slide. The rear arm of the lever f¹⁰ carries a cam-roll f¹³, which engages a peripheral cam-path (not shown) in the cam 2. The arrangement is such that a rotation of the 30 shaft a² will by the cams 2 and 3 and the levers f⁷ and f¹⁰ impart up-and-down and side-wise movements to the feed-point F, whereby said point will engage and impart a step-by-step sidewise feed movement to the work 35 in the direction of the arrows shown in Figs. 1 and 3.
- 40 The take-up lever G has at its outer end a take-up g g, and said lever is fulcrumed at g' on the shaft a⁶, and is provided at its inner end with a cam-roll g², which engages a cam-path (not shown) in the right-hand side of the cam 2, the arrangement being such that a rotation of the cam will impart an up-and-down movement to the take-up g g, as is usual 45 in these machines.
- 50 H indicates a slack - controller carried by double links h and h' and yieldingly held in engagement with the thread l by means of a spring h². The thread t leads from any suitable thread - waxing device (not shown) 55 through a tension device, (indicated diagrammatically at I,) thence over the first take-up roll g and under the slack-controller H, over the second take-up roll g, and thence 60 through the looper C.

All the parts of the machine thus far described may be constructed and organized in

a manner common to hook - needle chain-stitch machines and perform their several functions in a manner well-known to those skilled in the art, it being understood that the tension device has suitable mechanism to lock and release the thread, timed and arranged to coöperate with the component parts of the stitch-forming mechanism, all as will be described in a description of the operation of the machine which will be hereinafter set forth.

In the present invention as the needle is withdrawn from the work to draw up a loop 80 of thread the thread is locked at the tension device I in order to prevent the drawing off of thread from the source of supply, and the needle, still retaining the loop of thread in its hook, has imparted to it a sidewise movement in the direction of the feed of the work to exert a pull on the thread in the direction as illustrated in Fig. 3 of the drawings or away from the closed end of the loop of the preceding stitch, whereby (the thread being 90 locked at its source of supply) the thread forming the preceding stitch will be drawn upon and the loop of such stitch shortened, and as the needle is moved laterally in the opposite direction and up to its extreme backward stroke it will exert a pull upon the loop 95 thus shortened.

To secure the above-suggested result in the machine of the drawings, the needle b is mounted upon the usual needle-segment b', 100 which is fulcrumed at b² in a bracket b³, projecting forwardly from a slide b⁴, the said slide being fitted in a suitable guideway b⁵ and upon its rear face is provided with a rearwardly - projecting arm b⁶, which passes 105 through a slot b⁷ in the frame a³ and which carries a cam-roll b⁸, which engages a cam-path (not shown) in the cam 1. Any suitable mechanism may be provided for oscillating the needle-segment and imparting thereto its 110 movement in a forward direction to puncture the work and its movement in the rearward direction to draw up the loop of thread, the mechanism illustrated in the drawings comprising a segment-gear b⁹, which is fixedly secured to the stud b² of the needle-segment. 115 The segment-gear b⁹ is in engagement with a pinion b¹⁰, carried by the stud b¹¹ on the side of the bracket b³, and which in turn meshes with a wide rack b¹², carried by a lever b¹³, 120 fulcrumed upon the shaft a⁶ and having a rearwardly-extending arm carrying a cam-roll b¹⁴, which engages a cam-path (not shown) in the cam 1, the arrangement being such that a rotation of the shaft a² will impart to the 125 needle its work-puncturing and loop-drawing movements and also sidewise or lateral reciprocations, all as will be clear from an inspection of the drawings.

It will of course be understood that any suitable form of needle-guide o may be employed to strengthen the needle during its lateral stitch-setting movement.

In the operation of the machine the loop of

the preceding stitch formed by the needle is shortened by a pull on the loop of thread held by the needle and while the needle is retracted with a loop of thread the pull of such thread, 5 as before stated, being imparted in such a direction as to not bind or act on the loop of thread of the preceding stitch, which is the stitch being shortened—or, in other words, the pull exerted on the loop of thread held 10 by the needle will be in the direction of the feed of the work. As illustrated in the accompanying drawings, the machine is shown as uniting the welt and upper to the insole of a welted boot or shoe and the work being 15 positioned, as shown in Fig. 1, with the channel-guide D engaging the channel and the shoe held against the back gage, as in the usual manner of operating welt-sewing machines. The rotation of the main shaft will 20 by means of the cam and connecting mechanism, comprising the lever b^{13} , rack b^{12} , pinion b^{10} , and segment-gear b^9 , oscillate the needle-segment b' and project the needle b through the welt, the edge of the upper, and 25 the between substance of the insole, the point of the needle emerging from the channel. While the needle is in its forward position, the looper C is actuated to throw the loop of thread around the needle and into the hook 30 thereof. The needle is then retracted, drawing up the loop of thread. As the needle leaves the work the thread t is locked by the tension device and the slide b^4 moved laterally toward the left, as shown in Fig. 1 of the 35 drawings, thus exerting a loop-shortening pull on the loop of thread held by the needle and shortening the loop at the preceding stitch, and just before the needle reaches its extreme backward position the slide b^4 is re- 40 turned to the right and the needle completes its backward stroke. After the needle has completed its backward stroke it is again advanced toward the work, and during its advance movement the take-up or other slack-

controlling mechanism takes up the slack 45 thread from the needle, and just before the needle enters the work the feed-point F, which has been thrown into engagement with the work, is moved to the left, feeding the work a distance according to the length of the stitch 50 which it is desired to make and is then disengaged from the work and retracted toward the right preparatory to again engaging the work for another feed movement, thus causing the loop of the preceding stitch, which 55 has been shortened to less than the distance between two punctures in the work, to become straightened out and greatly facilitating the setting of the stitches. The needle is now advanced and enters the welt, as before, and emerges from the channel of the insole, and the looper is again actuated, as before described, to place another loop of thread in the needle and the needle retracted, drawing the second loop of thread through 60 the loop which has been previously formed, it being understood that during the advancement of the needle the take-up or other slack-controller is actuated to take up the slack 65 thread given up by the needle. 70

Having described the construction and operation of the illustrated embodiment of my invention, I claim as new and desire to secure by Letters Patent of the United States—

In a chain-stitch hook-needle sewing-machine, the combination with the needle and component parts of a stitch-forming mechanism, of means to impart a lateral thread-pulling movement to the needle in the direction of the feed of the work while the needle is 75 out of the work and retains the loop of thread, substantially as described.

In testimony whereof I affix my signature in presence of two witnesses.

JAMES W. MELOON.
